US00D736757S

(12) **United States Design Patent**
Kim et al.

(10) **Patent No.:** **US D736,757 S**
(45) **Date of Patent:** **** Aug. 18, 2015**

(54) **COVER FOR MOBILE PHONE**

(71) Applicant: **Samsung Electronics Co., Ltd.**,
Suwon-si (KR)

(72) Inventors: **Yoon-young Kim**, Seongnam-si (KR);
Min-a Oh, Gwangju-si (KR); **Yong Seo**,
Seoul (KR)

(73) Assignee: **Samsung Electronics Co., Ltd.**,
Suwon-si (KR)

(**) Term: **14 Years**

(21) Appl. No.: **29/470,218**

(22) Filed: **Oct. 18, 2013**

(30) **Foreign Application Priority Data**

Aug. 30, 2013 (KR) 30-2013-0044835

(57) **CLAIM**

The ornamental design for a cover for mobile phone, as
shown and described.

DESCRIPTION

FIG. 1 is a front perspective view of a cover for mobile phone
showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The dot-dash broken line shown in FIGS. 1 and 2 represents
a boundary of the claimed design. The dash-dash broken lines
throughout the drawing FIGS. illustrate unclaimed portions
of the cover for mobile phone.

1 Claim, 7 Drawing Sheets
